ELASTIC WAVE VIBRATOR

Harry W. Kompanek, Santa Barbara, Calif., assignor to Acoustica Associates, Inc., Mineola, N.Y., a corporation of New York

Filed July 6, 1959, Ser. No. 825,143
28 Claims. (Cl. 310—9.6)

This invention relates in general to elastic wave vibrators, and more particularly to electromechanical transducers which are especially suitable for low frequency operation and methods of manufacturing the same.

Among the most widely used forms of electromechanical transducers is the form in which the physical size of the transducer is related to the wavelength therein of elastic waves at the operating frequency (e.g., they are resonant vibrators). Common among embodiments of this form is the half-wave longitudinal vibrator, which is one or more half wavelengths long with respect to such wavelength. Due to the relatively high speed of elastic waves in materials commonly used in such transducers (piezoelectric, electrostrictive, for example), half-wave longitudinal and other forms of electromechanical vibrators made of these materials become prohibitively bulky, heavy and costly when designed for use at lower frequencies, such as the lower audible frequencies. Thus, heretofore half-wave transducers have been commonly found in sizes intended for use at 20 kc./sec., 40 kc./sec., and higher, but rarely are they found designed for operation at frequencies below 9 or 10 kc./sec. It is an object of the present invention to provide electromechanical transducers which are capable of being operated as resonant vibrators at lower frequencies with little or no increase in physical size. Another object is to provide methods and means to reduce by approximately half or more the frequency at which a given transducer can be operated as a resonant vibrator.

Electromechanical transducers made of certain electrostrictive materials, such as barium titanate and lead zirconium titanate, are advantageously prepolarized by the application of unidirectional potential to them. The voltage required to achieve a useful degree of prepolarization increases, for a given material, with the thickness of the body of the material across which the voltage is applied. This places a limitation upon the thickness of material across which prepolarizing voltage can be applied, for eventually the voltage required is so high that voltage breakdown is an expected possibility. The methods and structures of the invention which provide the feature of reduced resonance frequency for a given piece of transducer material also make it possible usefully to polarize a large body of transducer material in sections at lower voltage than would be possible in polarizing the same body as a unit. It is accordingly another object of the invention to provide methods and means for achieving useful polarization of electrostrictive transducer materials at polarization voltages which are reduced with respect to the voltages normally used heretofore, and with no sacrifice in the degree of resulting polarization.

According to the invention, a body of material suitable for use as an electromechanical transducer or vibrator intended for vibration in a given direction is perforated, for example, drilled out, in a direction transverse to the direction of vibration. The body is preferably provided with a plurality of such perforations, which may be scattered indiscriminately, or arrayed throughout the body in a prescribed manner. These perforations have the effect of reducing by as much as half or more the velocity of elastic wave energy through the body in the intended vibrational mode, thereby correspondingly reducing the wavelength of such vibration at a given frequency of

2

vibration. Thus, for example, a body of lead zirconium titanate, which in the unperforated state has a frequency constant "K_f" equal to 1400 kc./sec./mm. of thickness, can be perforated to an extent that it has a frequency constant K_f of 900 kc./sec./mm. of thickness and is still useful as an electromechanical transducer. Similarly, for barium titanate, K_f can be reduced from a value of 2400 kc./mm. to approximately 1600 kc./mm. by providing it with perforations according to the invention. It is accordingly another object of the invention to provide methods and means for reducing, by a factor of the order of half or more, the velocity of elastic wave energy in solid bodies.

According to another feature of the invention, an elongated piezoelectric transducer, for example, a half-wave vibrator, is provided with a series of transverse perforations which are arrayed side-by-side along a given longitudinal line (for example, a median line on one or both or two opposite side surfaces), and electrodes in the shape of bands of electrically conductive material are applied to the stem regions of the piezoelectric material between each perforation and one or both of the other two side surfaces. Polarizing voltage is then applied between each pair of adjacent electrodes displaced 15 in the longitudinal direction, at a voltage level sufficient to polarize the section of the transducer material from one electrode to the next. This voltage is a fraction of the voltage which would be required to achieve the same polarization of the entire body of piezoelectric material 20 if applied across the entire body, from one end to the other, the fraction being approximately the reciprocal of the number of sections individually polarized. By polarizing the successive sections of the piezoelectric material in relatively opposite senses, and connecting together the alternate electrodes to one terminal and the intervening electrodes to another terminal, the body can be operated 25 as a unitary electromechanical transducer.

Other and further features of the invention will become apparent from the following description of certain embodiments thereof. This description refers to the accompanying drawing, wherein:

FIG. 1 is an isometric view of a piezoelectric transducer in the form of a longitudinal vibrator;

FIG. 2 is a cross-section along line 2—2 in FIG. 1;

FIG. 3 illustrates electrical connections useful with the embodiment of FIG. 1;

FIG. 4 is another embodiment of the invention;

FIG. 5 is a view partly isometric and partly in section of a third embodiment of the invention;

FIG. 6 is an isometric view of still another embodiment made of magnetostrictive laminations; and

FIG. 7 is a side view of another embodiment of the invention.

Referring now to FIGS. 1 and 2, a body 10 of polarizable piezoelectric material, for example barium titanate or lead zirconium titanate, having length L, thickness T and width W, is intended for operation as a longitudinal vibrator, that is a vibrator which executes elongation and contraction in the direction of its length L. The length L is, in the present example, equal to one-half wavelength in the body 10 of vibrations therein at the operating frequency in said direction. A plurality of perforations 11, 12, 13, 14, and 15 pass through the body 10 transversely to the length dimension L, from one of the narrower side surfaces 16 to the other 17. These perforations are round being made by drilling, for example, but other shapes may be used if desired. The diameters of the perforations shown in FIG. 1 are equal approximately to half the thickness T of the body 10. An individual electrical conductor in the shape of a band 21, 22, 23, 24, 25, 26, 27, 28, 29, 30 surrounds each stem 40 region of the body 10 between each perforation 11, 12,

13, 14, 15 and the two wider side surfaces 34 and 35, respectively of the body 10. Two such stem regions 36 and 37 are shown in cross section in FIG. 2, and these are representative of all such stem regions. The individual electrodes 21 and 22 surrounding these two stem regions, respectively, are also shown in FIG. 2 illustrating the structure of all the electrodes 21-30, inclusive.

5 The method of polarizing the embodiment of FIGS. 1 and 2, and the mode of using it, are illustrated with the aid of FIG. 3, which shows, diagrammatically, the transducer body 10, perforations 11-15, inclusive, and electrodes 21-30, inclusive.

Polarization

The strength of a D.C. field required for polarization of barium titanate ceramic is about 12,000 volts per centimeter of thickness of this material between the polarizing electrodes. In practice higher voltages are used. Thus, for barium titanate it is usual to polarize at about 60,000 volts per inch of thickness while for lead zirconium titanate it is usual to use 120,000 volts per inch of thickness. Assuming that the length L of the body 10 in FIG. 1 is six inches, it would require in excess of 700,000 volts at this rate to polarize lead zirconium titanate through electrodes 38.1 and 39.1 affixed to the ends 38 and 39 of the body. The perforations 11 to 15, inclusive, however, divide the body 10 into six sections 10.1 to 10.6, inclusive, each of which is approximately one inch long. By applying 120,000 volts between each pair of adjacent electrodes (in the longitudinal direction L), such as between electrodes 21 and 23, for example, the section (in the present example section 10.2) between them can be polarized as effectively as if it were separated from the rest of the body 10. Preferably this voltage is applied between both electrodes 21 and 22 at one perforation 11 and both electrodes 23 and 24 at the next perforation 12. As a convenience for both polarizing the body 10, and subsequently for using it as a transducer, the alternate pairs of electrodes 21, 22; 25, 26; and 29, 30 are connected together in parallel to one terminal 41, and the intervening electrodes 23, 24; and 27, 28 are connected together in parallel to another terminal 42. The application of approximately 120,000 volts polarizing potential across these terminals 41 and 42 polarizes the sections 10.2, 10.3, 10.4 and 10.5 between the electrodes 21, 22 and 23, 24; 23, 24 and 25, 26; 25, 26 and 27, 28; and 27, 28 and 29, 30, respectively, in alternately opposite sense, as indicated by the + and - signs in FIG. 3. If desired electrodes 38.1 and 39.1 may be affixed to the end surfaces 38 and 39, respectively, and these may be connected to the terminal 42 of the intervening electrodes 23, 24 and 27, 28, to polarize the end sections 10.1 and 10.6, in the sense shown on each in FIG. 3. As the number of perforations is increased, however, the utility of the end electrodes 38.1 and 39.1 decreases. In an embodiment of the invention according to FIGS. 1 and 2 employing twenty perforations in a body of lead zirconium titanate which was six-and-one-half inches long, so that each section of transducer material between successive electrode pairs was approximately one-third of an inch long, polarization using the circuit of FIG. 3 was carried out with 40,000 volts applied across the terminals 41 and 42, and the end electrodes 38.1 and 39.1 were omitted.

Operation as a Transducer

The circuit of FIG. 3 may be used without change to operate embodiments according to FIG. 1 as a transducer simply by connecting the terminals 41 and 42 to a load or a driver in any known manner. The body 10 vibrates as a unit of which the resonant frequency is determined by its length L, notwithstanding that it was polarized in sections and is driven or used as a receiver in similar sections.

Velocity Control

Assuming that the body 10 in FIG. 1 is lead zirconium

titanate six-and-one-half inches long, we have a longitudinal vibrator which is one-half wavelength long at an operating frequency of about 8-9 kc./sec. As was mentioned above, the frequency constant, K_f , of this material is about 1400 kc./sec./mm. thickness. As the thickness increases, the resonance frequency is reduced. The resonance frequency is found by dividing the length L of the body 10 into the frequency constant K_f , for a bar-shaped body like the body 10 in FIG. 1. Thus if $L=6.5$ inches; $L=165$ mm. (approx.), and

$$\frac{K_f}{L} = \frac{1400}{165} = 8.5 \text{ kc./sec.}$$

In the specific example mentioned above, having twenty perforations in the form of drilled holes arrayed as in FIG. 1, K_f was reduced to approximately 900 kc./sec./mm. In this embodiment, then, the resonance frequency of the bar 10 of length L became

$$\frac{K_f}{L} = \frac{900}{165} = 5.45 \text{ kc./sec.}$$

It has been found that the resonance frequency of a given bar is reduced in proportion to the amount of material which is removed from the body 10 by the transversely directed apertures (11-15, inclusive, in FIG. 1), and that at the same time the Q of the resulting transducer is also reduced. The limit to the amount of material that can be removed will be determined by the designer, taking into account for example the stiffness of the load into which the transducer is intended to work; as the Q of the transducer becomes smaller, the stiffness of the load begins to govern its effective Q. The frequency constant of a given body can be reduced by half or more, for many intended uses.

If barium titanate is used as the transducer material in place of lead zirconium titanate, the same principles are applicable; only the numerical values are changed. For example, polarizing voltages for barium titanate are about half those for lead zirconium titanate. For barium titanate, $K_f=2400$ kc./sec./mm. (approximately). A bar of barium titanate six-and-one-half-inches long and having twenty perforations through it according to FIG. 1 will have a value of $K_f=1600$ kc./sec./mm. (approximately). It will be appreciated that if more perforations are made in the body, they may have smaller diameters than those shown in FIG. 1, or the frequency constant may be made still lower, or both.

FIGS. 4, 5, 6, and 7 show other embodiments of the invention in which the velocity of elastic waves in the transducer body is reduced by perforations transverse to the direction of vibration; these embodiments do not incorporate the low voltage polarization feature of the embodiment of FIG. 1. In FIG. 4, a cylindrical piezoelectric body 50, intended to vibrate axially as indicated by the double-headed arrow 51, has electrodes 52 and 53 at its ends connected to terminals 54 and 55, respectively. A perforation 56 is provided in this body, directed diametrically through the body, so that it is transverse to the direction of vibration. Additional perforations 56.1 may be provided if desired according to the principles set forth above. While these will be transverse to the direction of vibration, they need not be parallel to each other.

FIG. 5 shows a disk-shaped cylindrical body 60, intended for radial vibration as indicated by the arrows 61. Axially directed perforations 62 are provided in this body, so that they are transverse to the direction of vibration. This body is shown as piezoelectric, but it may be magnetostrictive, if desired. The manner of driving it is not illustrated, since those skilled in the art know how to drive such bodies in a radial vibration mode. The perforations 62 may be arrayed equidistant from the center of the disk 60, if desired.

FIG. 6 illustrates a bar 70 of magnetostrictive material, made of laminations 70.1, 70.2, 70.3, 70.4, etc., in a well-known fashion. This bar is intended, like the body

10 of FIG. 1, for longitudinal vibration in the direction of the long dimension L. Perforations 71, 72, 73, 74 pass through the bar transversely to the longitudinal dimension, as in FIG. 1, and have the same effects as the perforations in FIG. 1. The bar may be supplied with a suitable coil 75 for use as a transducer and for polarizing purposes, in any well-known manner.

FIG. 7 illustrates a longitudinal vibrator 80, of length L, in which numerous perforations 81, 82, 83, etc. all passing through it transversely to the direction of vibration, are scattered indiscriminately over the surfaces of the bar through which they pass. As is indicated in FIG. 7, the perforations can be smaller, relative to the width or thickness of the bar, than those shown in FIG. 1. The number of these perforations can, however, be made so great that the frequency constant of the body 80 is reduced by half or more of the frequency constant of the unperforated body. The arrangement according to FIG. 7 enables a precise control of the frequency constant throughout the body 80.

The embodiments of the invention which have been illustrated and described herein are but a few illustrations of the invention. Other embodiments and modifications will occur to those skilled in the art. No attempt has been made to illustrate all possible embodiments of the invention, but rather only to illustrate its principles and the best manner presently known to practice it. Therefore, while certain specific embodiments have been described as illustrative of the invention, such other forms as would occur to one skilled in this art on a reading of the foregoing specification are also within the spirit and scope of the invention, and it is intended that this invention includes all modifications and equivalents which fall within the scope of the appended claims.

What is claimed is:

1. Method of reducing by substantially one-half the velocity of elastic wave vibrations substantially throughout a solid body intended for resonant vibration in a given direction which comprises perforating the vibration-propagating portion of said body completely through from one side to the opposite side thereof in a direction transverse to the direction of vibration at a plurality of locations throughout a resonant section of said body, whereby simultaneously to reduce the mass and increase the compliance of said body substantially uniformly throughout.

2. Method of polarizing an elongate body of piezoelectric material intended for resonant longitudinal vibration comprising the steps of perforating the vibration-propagating portion of said body completely through from one side to the opposite side thereof in a direction transverse to its longitudinal dimension, whereby simultaneously to reduce the mass and increase the compliance of said body substantially uniformly throughout at a plurality of locations along said dimension, and polarizing each longitudinal section of said body between adjacent pairs of said perforations in the sense opposite to the sense of the contiguous sections.

3. Method of producing a polarized elongate electro-mechanical transducer of piezoelectric material intended for resonant longitudinal vibration comprising the steps of perforating the vibration-propagating portion of said body completely through from one side to the opposite side thereof in a direction transverse to its longitudinal dimension at a plurality of locations along said dimension, polarizing each longitudinal section of said body between adjacent pairs of said perforations in the sense opposite to the sense of the contiguous sections and electrically connecting said sections for cumulative vibrational and electrical effects.

4. Method of polarizing an elongate body of piezoelectric material intended for resonant longitudinal vibration comprising the steps of perforating the vibration-propagating portion of said body completely through from

one side to the opposite side thereof in a direction transverse to its longitudinal dimension, whereby simultaneously to reduce the mass and increase the compliance of said body substantially uniformly throughout, applying an electrode to at least a portion of each stem region of said body between a perforation and a lateral surface of said body and employing adjacent pairs of said electrodes to polarize each longitudinal section of said body between adjacent pairs of said perforations in the sense opposite to the sense of the contiguous sections.

5. Method of producing a polarized elongate electro-mechanical transducer of piezoelectric material intended for resonant longitudinal vibration comprising perforating the vibration-propagating portion of said body completely through from one side to the opposite side thereof in a direction transverse to its longitudinal dimension at a plurality of locations along said dimension, whereby simultaneously to reduce the mass and increase the compliance of said body substantially uniformly throughout, applying an electrode to at least a portion of each stem region of said body between a perforation and a lateral surface of said body, employing adjacent pairs of said electrodes to polarize each longitudinal section of said body between adjacent pairs of said perforations in the sense opposite to the sense of the contiguous sections, connecting alternate ones of said electrodes to a first conductor, and connecting the intervening ones of said electrodes to a second conductor.

6. Electromechanical vibrator comprising a body of solid material intended for resonant vibration in a prescribed direction having a plurality of perforations passing completely through said body from one side to the opposite side thereof, each of which is located directly in the path of vibrations in said body and is directed transversely to the direction of vibration at a plurality of locations throughout a resonant section of said body, whereby simultaneously to reduce the mass and increase the compliance of said body substantially uniformly throughout.

7. Electromechanical vibrator comprising an elongated body of solid material intended for resonant vibration in the longitudinal direction having a plurality of perforations arrayed throughout a resonant section thereof passing completely through it directly in the vibrations path and transversely to the direction of vibration between two opposite side surfaces thereof, whereby simultaneously to reduce the mass and increase the compliance of said body substantially uniformly throughout.

8. Electromechanical vibrator comprising an elongated body of solid material intended for resonant vibration in the longitudinal direction and having a plurality of perforations passing completely through it directly in the vibrations path and transversely to the direction of vibration between two opposite side surfaces thereof, said perforations being arrayed indiscriminately on said side surfaces, whereby simultaneously to reduce the mass and increase the compliance of said body substantially uniformly throughout.

9. Electromechanical vibrator comprising an elongated body of solid material intended for resonant vibration in the longitudinal direction and having a plurality of perforations passing completely through it directly in the vibrations path and transversely to the direction of vibration between two opposite side surfaces thereof, said perforation being arrayed along a median line on each of said side surfaces, whereby simultaneously to reduce the mass and increase the compliance of said body substantially uniformly throughout.

10. Electromechanical vibrator comprising an elongated body of solid material intended for resonant vibration in the longitudinal direction and having a rectangular cross section, a plurality of perforations passing completely through said body directly in the vibrations path and transversely to the direction of vibration between the two opposite narrower side surfaces thereof, the cross-

sectional dimensions of said perforations being approximately half the thickness of said body, whereby simultaneously to reduce the mass and increase the compliance of said body substantially uniformly throughout by amounts which are sufficient substantially to reduce by the order of half the frequency constant of said material.

11. Electromechanical vibrator comprising an elongated body of solid material intended for resonant vibration in the longitudinal direction and having a rectangular cross section, a plurality of perforations passing completely through said body directly in the vibrations path and transversely to the direction of vibration between the two opposite narrower side surfaces thereof, said perforations being arrayed along a median line on each of said side surfaces and having cross-sectional dimensions which are approximately half the thickness of said body, whereby simultaneously to reduce the mass and increase the compliance of said body substantially uniformly throughout by amounts which are sufficient substantially to reduce by the order of half the frequency constant of said material.

12. Electromechanical vibrator comprising an elongated body of solid material intended for resonant vibration in the longitudinal direction and having a rectangular cross section, a plurality of perforations passing completely through said body directly in the vibrations path and transversely to the direction of vibration between the two opposite narrower side surfaces thereof, said perforations being arrayed substantially uniformly along a median line on each of said side surfaces and having cross-sectional dimensions which are approximately half the thickness of said body, whereby simultaneously to reduce the mass and increase the compliance of said body substantially uniformly throughout by amounts which are sufficient substantially to reduce by the order of half the frequency constant of said material.

13. Electromechanical vibrator comprising a cylindrical body of solid material intended for resonant vibration in the axial direction and having a plurality of perforations passing diametrically completely through it, said perforations being dimensioned to remove a quantity of said material which simultaneously reduces the mass and increases the compliance of said body by amounts sufficient substantially to reduce by the order of half the frequency constant of said material.

14. Electromechanical vibrator comprising a cylindrical body of solid material intended for resonant vibration in the radial direction and having a plurality of perforations passing through it directly in the vibrations path and in the axial direction from one end of said body to the other, said perforations being dimensioned to remove a quantity of said material which simultaneously reduces the mass and increases the compliance of said body by amounts sufficient substantially to reduce by the order of half the frequency constant of said material.

15. Electromechanical vibrator comprising a cylindrical body of solid material intended for resonant vibration in the radial direction and having a plurality of perforations each of which is axially directed, said perforations being arrayed substantially equidistant from the axis of said body, said perforations being dimensioned to remove a quantity of said material which simultaneously reduces the mass and increases the compliance of said body by amounts sufficient substantially to reduce by the order of half the frequency constant of said material.

16. Electromechanical vibrator comprising a cylindrical body of solid material intended for resonant vibration in the radial direction and having a plurality of perforations passing through it directly in the vibrations path and in the axial direction from one end of said body to the other, said perforations being arrayed substantially equidistant from the axis of said body, said perforations being dimensioned to remove a quantity of said material which simultaneously reduces the mass and increases the compliance of said body by amounts sufficient substan-

tially to reduce by the order of half the frequency constant of said material.

17. Electromechanical vibrator comprising an elongated body of piezoelectric material intended for resonant vibration in the longitudinal direction, said body having a plurality of perforations passing completely through it directly in the vibrations path and transversely to the direction of vibration between two opposite side surfaces thereof, said perforations being arrayed side-by-side in the direction of vibration, said perforations being dimensioned to remove a quantity of said material which simultaneously reduces the mass and increases the compliance of said body by amounts sufficient substantially to reduce by the order of half the frequency constant of said material, the sections of said body between each pair of adjacent perforations being permanently polarized in alternately reversing sense, said sections being electrically connected together for cumulative vibrational and electrical effects.

20. 18. Electromechanical vibrator comprising an elongated body of piezoelectric material intended for resonant vibration in the longitudinal direction and having a rectangular cross section, a plurality of perforations passing completely through said body directly in the vibrations path and transversely to the direction of vibration between the two opposite narrower side surfaces thereof, said perforations being arrayed along a median line on each of said narrower side surfaces and having cross-sectional dimensions which are approximately half the thickness of said body, said perforations being dimensioned to remove a quantity of said material which simultaneously reduces the mass and increases the compliance of said body by amounts sufficient substantially to reduce by the order of half the frequency constant of said material, the sections of said body between each pair of adjacent perforations being permanently polarized in alternately reversing sense.

19. Electromechanical vibrator comprising an elongated body of piezoelectric material intended for resonant vibration in the longitudinal direction, said body having a plurality of perforations passing completely through it directly in the vibrations path and transversely to the direction of vibration between a first pair of opposite side surfaces thereof, said perforations being arrayed side-by-side in the direction of vibration, said perforations being dimensioned to remove a quantity of said material which simultaneously reduces the mass and increases the compliance of said body by amounts sufficient substantially to reduce by the order of half the frequency constant of said material, and a separate band-shaped electrode surrounding at least one of the two stem regions of said material between each of said perforations and the remaining pair of side surfaces of said body.

55. 20. Electromechanical vibrator comprising an elongated body of piezoelectric material intended for resonant vibration in the longitudinal direction, said body having a plurality of perforations passing completely through it directly in the vibrations path and transversely to the direction of vibration between a first pair of opposite side surfaces thereof, said perforations being arrayed side-by-side in the direction of vibration, said perforations being dimensioned to remove a quantity of said material which simultaneously reduces the mass and increases the compliance of said body by amounts sufficient substantially to reduce by the order of half the frequency constant of said material, and a separate band-shaped electrode surrounding each of the stem regions of said material between each of said perforations and the remaining pair of side surfaces of said body.

60. 21. Electromechanical vibrator comprising an elongated body of piezoelectric material intended for resonant vibration in the longitudinal direction, said body having a plurality of perforations passing completely through it directly in the vibrations path and transversely to the direc-

75

tion of vibration between a first pair of opposite side surfaces thereof, said perforations being arrayed side-by-side in the direction of vibration, said perforations being dimensioned to remove a quantity of said material which simultaneously reduces the mass and increases the compliance of said body by amounts sufficient substantially to reduce by the order of half the frequency constant of said material, the sections of said body between each pair of adjacent perforations being permanently polarized in alternately reversing sense, and a separate band-shaped electrode surrounding at least one of the two stem regions of said material between each of said perforations and the remaining pair of side surfaces of said body.

22. Vibrator according to claim 21 in which the electrodes at alternate ones of said perforations are electrically connected together, and the electrodes at the intervening ones of said perforations are electrically connected together.

23. Electromechanical vibrator comprising an elongated body of piezoelectric material intended for resonant vibration in the longitudinal direction and having a rectangular cross section, a plurality of perforations passing completely through said body directly in the vibrations path and transversely to the direction of vibration between the two opposite narrower side surfaces thereof, said perforations being arrayed along a median line on each of said narrower side surfaces and having cross-sectional dimensions which are approximately half the thickness of said body, whereby simultaneously to reduce the mass and increase the compliance of said body substantially uniformly throughout by amounts which are sufficient substantially to reduce by the order of half the frequency constant of said material, the sections of said body between each pair of adjacent perforations being permanently polarized in alternately reversing sense, and a separate band-shaped electrode surrounding each of the stem regions of said material between each of said perforations and the wider side surfaces of said body.

24. Vibrator according to claim 23 in which the electrodes at alternate ones of said perforations are electrically connected together, and the electrodes at the intervening ones of said perforations are electrically connected together.

25. In an elastic wave vibrator comprised of a body of a solid material which in the uniform uninterrupted state 45 has a known frequency constant with respect to elastic

5 wave vibrations therein parallel to a prescribed direction therethrough, means to reduce the magnitude of the frequency constant of said body with respect to such vibrations therein comprising a plurality of perforations in said body passing completely through said body from one side to the opposite side thereof transverse to said prescribed direction, said perforations being directly in the path of such vibrations.

26. In an elastic wave vibrator comprised of an elongated body of a solid material which in the uniform uninterrupted state has a known frequency constant with respect to elastic wave vibrations therein parallel to the length direction thereof, means to reduce the frequency constant of said body with respect to such vibrations comprising a plurality of perforations in said body passing completely through said body from one side to the opposite side thereof transverse to said length direction, said perforations being directly in the path of such vibrations.

27. In an elastic wave vibrator comprised of a cylindrical body of a solid material which in the uniform uninterrupted state has a known frequency constant with respect to radially-propagating elastic wave vibrations therein, means to reduce the frequency constant of said body with respect to such vibrations comprising a plurality of perforations in said body passing completely through said body in the axial direction, said perforations being directly in the path of such vibrations.

28. In an elastic wave vibrator comprised of a cylindrical body of a solid material which in the uniform uninterrupted state has a known frequency constant with respect to axially-propagating elastic wave vibrations therein, means to reduce the frequency constant of said body with respect to such vibrations comprising a plurality of perforations in said body passing diametrically completely through said body, said perforations being directly in the path of such vibrations.
